CLAIM

The ornamental design for a retaining wall block, as shown and described.

DESCRIPTION

FIG. 1 is a front perspective view of a first embodiment of a retaining wall block of the present invention;

FIG. 2 is a side view, as taken from the left side of the retaining wall block of FIG. 1;

FIG. 3 is a side view, as taken from the right side of the retaining wall block of FIG. 1;

FIG. 4 is a first end view of the retaining wall block of FIG. 1;

FIG. 5 is a second end view of the retaining wall block of FIG. 1;

FIG. 6 is a top plan view of the retaining wall block of FIG. 1;

FIG. 7 is a bottom plan view of the retaining wall block of FIG. 1;

FIG. 8 is a front perspective view of a embodiment of the retaining wall block of the present invention.

FIG. 9 is a side view, as taken fro the left side of the retaining wall block of FIG. 8;

FIG. 10 is a side view, as taken from the right side of the regaining wall block of FIG. 8;

FIG. 11 is a first end view of the retaining wall block of FIG. 8;

FIG. 12 is a second end view of the retaining wall block of FIG. 8;

FIG. 13 is a top plan view of the retaining wall block of FIG. 8;

FIG. 14 is a bottom plan view of the retaining wall block of FIG. 8;

FIG. 15 is a front perspective view of a third embodiment of a retaining wall block of the present invention;

FIG. 16 is a side view, as taken from the left side of the retaining wall block of FIG. 15;

FIG. 17 is a side view, as taken from the right side of the retaining wall block of FIG. 15;

FIG. 18 is a first end view of the retaining wall block of FIG. 15;

FIG. 19 is a second end view of the retaining wall block of FIG. 15;

FIG. 20 is a top plan view of the retaining wall block of FIG. 15;

FIG. 21 is a bottom plan view of the retaining wall block of FIG. 15;

FIG. 22 is a front perspective view of a fourth embodiment of the retaining wall block of the present invention;

FIG. 23 is a side view, as taken from the left side of the retaining wall block of FIG. 22;

FIG. 24 is a side view, as taken from the right side of the retaining wall block of FIG. 22;

FIG. 25 is a first end view of the retaining wall block of FIG. 22;

FIG. 26 is a second end view of the retaining wall block of FIG. 22;

FIG. 27 is a top plan view of the retaining wall block of FIG. 22; and,

FIG. 28 is a bottom plan view of the retaining wall block of FIG. 22.
